United States Patent Office

Des. 195,253
Patented May 21, 1963

195,253

LOG CABIN

Charles G. Rist, Rte. 2, Box 115, Fallston, Md.

Continuation of design application Ser. No. 58,892, Jan.
4, 1960. This application Jan. 2, 1962, Ser. No. 68,353

Term of patent 14 years

(Cl. D13—1)

FIG. 3

FIGURE 1 is a perspective view showing the front and side of a log cabin showing my new design.

FIGURE 2 is a view of the end of the log cabin not shown in FIGURE 1.

FIGURE 3 is a rear view of the log cabin.

This application is a continuation of application Serial No. D. 58,892 dated January 4, 1960, and now abandoned.

I claim:

The ornamental design for a log cabin, substantially as shown.
